GEAR LAPPING APPARATUS

John M. Christman, Detroit, Mich., assignor to
 Packard Motor Car Company, Detroit, Mich., a
 corporation of Michigan

Application November 30, 1936, Serial No. 113,491

15 Claims. (Cl. 51—157)

This invention relates to apparatus for improving radially toothed machine elements such as gears and the like and is more particularly concerned with the lapping or grinding of gear teeth after the formation of the teeth by the usual milling, hobbing, shaving or other cutting operations, and either before or after hardening.

It is common practice in the art to which this invention relates to improve the meshing of toothed gears by a lapping operation which involves the engaging of the gears with a lap member having corresponding teeth and effecting relative reciprocation between the gear and the lap members, a suitable abrasive being supplied to the cooperating toothed surfaces. For example, an externally toothed gear and an internally toothed lap, the latter being preferably hardened and having teeth affording therebetween recesses within which the gear teeth may be received snugly or with a slight clearance, are aligned axially and are reciprocated in an axial direction, means being provided to simultaneously urge one of the cooperating members to rotate with respect to the other to apply circumferential pressure between the cooperating teeth.

A machine adapted to perform the described operation is disclosed in my application Serial No. 17,728, filed April 22, 1935, and the present invention contemplates an improvement thereof. The machine in question comprises, generally, means for supporting a lap, means for supporting a gear for vertical reciprocation in engagement with the lap, and driving means for producing the said reciprocal motion. According to said disclosure, the gear to be lapped is secured at the end of a vertical shaft by means of a nut or other conventional device for securing the gear rigidly to the shaft. Inasmuch as it is desirable to release the gear from such rigid engagement at frequent intervals for the purpose of indexing the gear with respect to the lap, or of exchanging a new gear for a finished one, the present invention is directed to novel and improved means for elevating the gear out of engagement with the lap, and for facilitating engagement and disengagement of the gear and shaft in order to permit the speedy accomplishment of the aforesaid operations.

A further object of the present invention is the provision of suitable means for engaging, and securing to the shaft, gears of special forms, for example, of the various types customarily employed in the transmissions of motor vehicles. Other and further objects, features and advantages will appear from the description which

follows, together with the accompanying drawings in which:

Figure 1 is a side elevation of a gear lapping machine to which the present invention is applicable;

Figure 2 is a vertical section of the gear engaging mechanism of Figure 1;

Figure 3 is a vertical section of a modified form of gear engaging mechanism;

Figure 4 is a front elevation of the mechanism of Figure 3;

Figure 5 is a bottom view of the mechanism of Figure 4;

Figure 6 is a horizontal section on line 6—6 of Figure 4;

Figure 7 is a vertical longitudinal section of a second form of gear engaging mechanism embodying the present invention;

Figure 8 is a vertical transverse section of a portion of the mechanism of Figure 7;

Figure 9 is a fragmentary section on line 9—9 of Figure 8;

Figure 10 is an exploded view of a portion of the mechanism of Figures 7 and 8;

Figure 11 is a vertical section of a third form of gear engaging mechanism embodying the present invention;

Figure 12 is an enlarged detail of the gear engaging means of Figure 11;

Figure 13 is a horizontal section on line 13—13 of Figure 12;

Figure 14 is a horizontal section on line 14—14 of Figure 11;

Figure 15 is a vertical section of a still further form of gear engaging mechanism embodying the present invention;

Figure 16 is a horizontal section on line 16—16 of Figure 15;

Figure 17 is a horizontal section on line 17—17 of Figure 16; and

Figure 18 is an enlarged detail of the gear engaging means of Figure 15.

In order to facilitate an understanding of the invention, reference is made to the embodiment thereof shown in the accompanying drawings and detailed descriptive language is employed. It will nevertheless be understood that no limitation of the invention is thereby intended and that various changes and alterations are contemplated such as would ordinarily occur to one skilled in the art to which the invention relates.

As set forth above, the gear lapping machine to which the present invention is applicable is adapted to impart relative reciprocal movement between a gear and a lap, and the particular

15

20

25

30

35

40

45

55

embodiment disclosed herein provides for such reciprocal movement in a vertical direction. More specifically, the machine illustrated in Figure 1 is of the type in which the lap is provided with an internal toothed portion and is retained against movement, the gear having external teeth and being reciprocated in meshing relation with the lap. Thus the machine may comprise a frame including a base 10 and a head portion 11 overlying the base, the head portion being supported by a standard 12 rising from the base. Gear engaging mechanism 13, which will be hereinafter more fully described, is provided with an upwardly directed boss 14 which may be keyed or otherwise secured against rotation on a shaft 15. The gear engaging mechanism is rigidly secured, at its upper end, to the shaft 15 by suitable clamping mechanism indicated at 16. Shaft 15 is supported adjacent the upper end thereof in a bearing guide 17 and is operatively connected by means of a pitman 18 to an eccentric 19 formed on or secured to a shaft 20, the latter being carried by the head portion of the frame and having secured thereto at its outer end a pulley 21 which may be driven by a belt 22 from a motor 23.

It will be appreciated that by means of the mechanism thus far described, rotation of the shaft 20 will effect reciprocation of the shaft 15 and the gear engaging mechanism 13. The latter engages and supports the gear to be lapped in meshing relation with a stationary lap 24 which may be supported rigidly on the base 10 of the frame in any suitable manner.

Mechanism for imparting rotary motion to the shaft 15 and gear engaging mechanism 13 is indicated generally at 25, but since this mechanism forms no part of the present invention, it will not be further described.

The gear engaging mechanism illustrated in Figure 2 is particularly adapted for use in lapping gear clusters such as are commonly employed in automotive transmissions and is illustrated in connection with a gear cluster 26 comprising a shaft 27 provided with gears 28, 29, 30, and 31, formed integrally therewith. It will be appreciated that each of the gears comprising the cluster will be lapped in a separate operation, and it is obvious that the vertical relationship between the reciprocating shaft 15 and the lap 24 will be different for each gear. This variable relationship may be accomplished by the provision of suitable means for adjusting the position of the lap and/or the length of the shaft 15, but most expediently the several operations referred to are performed in several machines, each machine being adapted to lap one particular gear of the cluster. The machine illustrated in Figure 1 is arranged and adapted for lapping the lower-most gear 31 of the cluster.

The gear engaging mechanism illustrated in Figure 2 comprises a casing 40 in which is slidably mounted a sleeve 41 which is pivotally supported as at 42 by a link 43. The latter is pivoted at 44 to a crank arm 45 carried by a shaft 46, upon the outer end of which is secured a lever 47 (Figure 1). A shaft 48 is secured within the sleeve 41 by means of a pin 49 which extends through a slot 50 formed in the shaft 48, thereby permitting limited relative movement between the latter and the sleeve 41. The shaft 48 is provided with a head 51 which is adapted for centering the gear cluster 26, in the manner illustrated. A collar 52 surrounds the shaft 48, being

supported by the head 51, and between the lower end of the sleeve 41 and the collar 52 there are provided a number of disc springs 53, whose function will be described hereinafter. A carrier 54 is threaded upon the lower end of the casing 40 and is provided with a removable gear supporting member 55, the bearing surface between the carrier and gear supporting member being spherical and both the carrier and the gear supporting member being slotted as at 56 to permit the lateral insertion and removal of the shaft 27 of the gear cluster 26. By reason of the spherical bearing surface between the gear supporting member 55 and the carrier 54, the former is enabled to compensate for any lack of parallelism between the respective faces of the gear 28, which is gripped between the gear supporting member 55 and the collar 52.

It will be apparent from the foregoing description that when the lever 47 is in its lower position as illustrated in Figure 1, and the various parts of the gear engaging mechanism therefore occupy the positions illustrated in Figure 2, the gear 28 will be securely gripped between the gear supporting member 55 and the collar 52, the disc springs 53 serving to compensate for any variation in the thickness of the successive gears to be lapped. In this position, the lower-most gear 31 is in engagement with the lap 24 as seen in Figure 1, and the lapping operation may be commenced. When it is desired to index the gear so as to engage its teeth with different teeth of the lap, the lever 47 is raised whereupon, by means of the described linkage, the sleeve 41 will be elevated, carrying with it the shaft 48 and collar 52, thus releasing the gear 28. The operator may then manually lift the gear cluster, by taking hold of the gear 28 and rotating it to the desired extent. Upon completion of the lapping operation, the gear 28 may be released in the described manner, and the gear cluster raised until the gear 31 is disengaged from the lap, whereupon the gear cluster may be removed laterally through the slot 56 and a new gear cluster inserted.

It will be apparent from the foregoing that the described mechanism provides means whereby the insertion, indexing, and removal of successive gear clusters may be easily accomplished in a fraction of the time which would be required in securing or releasing a gear secured by bolts or other conventional means.

The gear engaging mechanism illustrated in Figures 3-6 is adapted for use in connection with machines intended for lapping gears 29 and 30 of the cluster 26, and differs functionally from the mechanism of Figure 2 in that it provides for moving the gear cluster through a greater distance in order to engage and disengage the lap and the gear to be lapped. It will be obvious, for example, that in placing the gear 29 in engagement with a lap, the portion of the cluster beyond gear 29 and including gears 30 and 31 must be projected through the lap, thus requiring a more extensive movement of the gear cluster than is the case when gear 31 is to be lapped. Thus, also, when the cluster is to be removed from the machine, it will be necessary to elevate it until the gear 31 reaches a point above the lap 24 before the gear cluster may be removed laterally through the slot in the carrier. In order to provide for the aforesaid extended movement, the mechanism illustrated in Figures 3-6 comprises a casing 60 in which is slidably

mounted a carrier 61, keyed to the casing 60 by means of pins 62. Within the carrier 61 is slidably mounted a sleeve 63, which is connected to a shaft 64 by means of a link 65 and crank arm 66, just as in the case of the mechanism previously described. The carrier 61 is provided with a removable gear supporting member 67, also as in the case of the previously described form of the invention. A shaft 68 is mounted 10 within the sleeve 63 and secured thereto by means of a pin and slot engagement as indicated at 69. A collar 70 supported by the head 71 of the shaft 68 is urged downwardly by the disc springs 72 surrounding the shaft 68.

15 It is believed that the operation of the described mechanism will be readily understood. With the parts in the position illustrated the gear 28 is securely gripped between the collar 70 and the gear supporting member 67, the springs 72 serving to compensate for variations in thickness of successive gears. If it is desired to elevate the gear cluster for indexing, or to remove it and substitute another piece of work, the lever 73 is elevated, rotating the shaft 64 and with it the crank arm 66, thus raising the sleeve 63 and releasing the grip of the collar 70 upon the gear 28. However, since the lower portion of the gear cluster is projecting below the lap, it is apparent that the entire gear cluster must be elevated to 25 a considerable extent before its removal will be possible. This may be accomplished by further elevating the lever 73 when the collar 70 will be brought against the surface 74 of the carrier 61, elevating the latter until the surface 75 engages the lower end of the casing 60. The gear 31 will then be above the lap and the gear cluster may be removed laterally as previously described. It will be obvious that the gear may be indexed by raising it to an intermediate position and manually rotating it by taking hold of gear 28.

Rotation of the collar 70 is prevented by the ears 76 (Figure 6), and rotation of the gear supporting member 67 is prevented by means of a pin 77 engaging a slot 78 in the gear supporting member (Figure 4). Thus, rotation of the gear cluster, when in operative position, is effectively prevented.

The gear engaging mechanism of Figures 7-10 is adapted for use in connection with gears such as that illustrated in Figure 7, which is of the type commonly employed as a reverse gear in automotive transmissions. In this embodiment of the invention there is employed a casing 80 comprising an upper section 81 and lower section 82 connected by bolts 83. A carrier 84 is slidably mounted within the casing 80 and is connected with a shaft 85 by means of a link 86 and crank arm 87. The upper end of the carrier 84 is formed in two sections 88 and 89 adapted to be bolted together and providing space therebetween for receiving the disc springs 90, which are employed for the same purpose as that described in connection with the previous embodiments of this invention, sufficient vertical clearance being provided between the sections 88 and 89 to permit slight relative movement thereof, whereby downward thrust applied by the link 86 may be transmitted through the springs. A bearing extension 91 is threaded into the lower end of the carrier 84 and is adapted to engage the upper side of the gear 92. A shaft 93 extends through the bearing member 91 and carrier 84 and is provided with a cross-head 94, secured 75 by means of a pin 95. Opposed flanges 96 formed

upon the cross-head 94 are provided with serrations 97 adapted to engage corresponding serrations 98 formed upon a ring 99 carried by the casing 80, thus preventing rotation of the shaft 93.

With the parts in lowered position as illustrated in Figure 7, the gear 92 is firmly gripped between the bearing member 91 and a gear supporting member 100, secured at the end of shaft 93 by means of a bolt 101, and is at its lower-most position, in engagement with its lap. When the lever 102 is elevated, the carrier 84 rises, carrying with it the bearing member 91, thus releasing the gear 92. Further movement of the lever 102 will cause the shoulder 103 of the carrier 84 to 15 engage the underside of the cross-head 94 of the shaft 93, elevating the latter and with it the gear 92, thus taking the latter out of mesh with its lap. The gear 92 may then be manually indexed and again lowered into engagement with 20 the lap, or it may be removed and a new gear substituted, by unscrewing the bolt 101 and removing the gear supporting member 100.

In order to support the movable mechanism in elevated position during a change of gears, spring 25 pressed dogs 104 are provided in the casing (Figures 8, 9) and are adapted to engage in depressions 105 formed in the crank arm 87.

The form of gear engaging mechanism illustrated in Figures 11-14 is especially adapted for use with a gear 109 of the type best shown in Figure 12, having a second set of teeth, for example, clutch teeth, spaced from the gear teeth to be lapped. In this form of the invention the carrier 110 is slidably mounted within a casing 111, and within the carrier 110 is slidably mounted a cylindrical member 115, which is keyed to the carrier 110 as at 116. A shaft 117 is pinned to the member 115 as at 118, permitting relative rotary motion therebetween, as well as limited 30 relative vertical displacement. The head 119 of the shaft 117 is connected to the shaft 112 by means of a link 113 and a crank arm 114, and a plurality of disc springs 120 are interposed between the head 119 and the cylindrical member 45 115, for the purpose stated in connection with the previously described forms.

A toothed ring 121, secured at the bottom of the casing 111, engages corresponding teeth 122 formed on the carrier 110, preventing relative rotation between the casing and carrier. Seated near the lower end of the member 115, and retained by any suitable means, such as a collar 123, disc 124 and bolt 125, is an annular member 126 having a downwardly projecting flange 127 50 which is toothed at its lower edge. Coil springs 128 are interposed between the carrier 110 and annular member 126. A spring ring 129 is seated in a groove formed adjacent the lower end of the carrier 110, and one end of the ring 129 projects 60 through an aperture 130 in the wall of the carrier. Internally of the extreme lower end of the carrier are formed teeth 131, corresponding in number to the clutch teeth 132 of the gear 109.

The gear 109 may be inserted in the engaging 65 mechanism by first rotating shaft 112 by means of a lever (not shown) so as to raise the carrier 110 into engagement with a shoulder 133 formed on the casing 111, when further upward movement of crank 114 will result in compression of springs 70 128 and seating of the annular member 126 against the carrier 110. With the parts in this position, the clutch teeth 132 of the gear 109 may be passed upwardly between the teeth 131, after which the gear is rotated a distance of one half 75

tooth. When this has been done the inwardly projecting end of the ring 129 will be engaged between two of the clutch teeth (Figure 13) and the latter will rest on top of the teeth 131 of the carrier. If now the shaft 112 is rotated so as to lower the mechanism out of engagement with the shoulder 133, springs 128 will cause the annular member 126 to be depressed until the downwardly projecting teeth thereon are seated between the clutch teeth 132 of the gear 109, the latter being securely retained against vertical or rotary motion relative to the engaging mechanism. Further rotation of the shaft 112 will then lower the mechanism until the gear 109 engages its lap.

By reversing the foregoing steps the gear 109 may be removed. In order to index the gear it is only necessary to elevate the mechanism until the gear 109 is clear of the lap. The teeth 122 of the carrier will then be disengaged from the toothed ring 121, and the gear carrier 113 and gear 109 may be rotated manually to effect the desired indexing operation.

The mechanism of Figures 15-18 is adapted for engaging a gear 150 of the type having internal helical teeth. Here a carrier 151 is slidably mounted within a casing 152, and is connected with a shaft 153 by the link 154 and crank arm 155. The enlarged upper portion of the carrier 151 is in two sections, a head 156 and a sleeve 157, threaded together, the latter being flanged as at 148. The lower cylindrical member 149 of the carrier 151 is provided with an annular shoulder 147, overlying the flange 146 and forming therewith a vertical driving connection between the upper and lower portions of carrier 151, while permitting relative rotary motion therebetween. The disc springs 158 are disposed between the head 156 and the cylindrical member 149 for a purpose generally similar to that previously explained in connection with the other embodiments. A shaft 159 extends centrally of the carrier 151, and is provided with a cross-head 160, extending through slot 146 in the cylindrical member 149, the toothed ends of which cross-head engage with a correspondingly toothed ring 161, secured to the casing 152, in order to prevent rotation of the shaft 159 and member 149, relative to the casing 152.

A helically toothed member 162 is threaded into the lower end of member 149, and is splined to shaft 159 as at 163. A second helical toothed member 164 is keyed onto the end of shaft 159, being retained in place by a nut 165. A coil spring 166 surrounds the shaft 159, and is under compression between the member 162 and a collar 167, which is in turn retained by a pin 168. The shaft 159 and member 164 are thus normally urged upwardly relative to the carrier 151 and member 162.

A pin 169, slidably carried in the head of the carrier 151, rests upon the cross-head 160 of shaft 159, and in turn supports a flanged disc 170. If the mechanism is elevated, by rotating shaft 153, until the flanged disc 170 encounters the shoulder 171 of the casing 152, any further rotation of the shaft 153 will cause the carrier 151 to be slightly raised with respect to shaft 159, compressing spring 166, and moving toothed member 164 away from member 162. When in this position the helical teeth of the respective members align to form, in effect, a single set of helical teeth, matching the internal helical teeth of the gear 150. The latter may be slipped into place on the members 162 and 164, after which

the mechanism is released to permit the spring 166 to come into play, urging the shaft 159 and member 164 upwardly with respect to carrier 151 and member 162. This slight movement results in a wedging action between the teeth of the members 162 and 164 and the internal teeth of gear 150, securing the latter rigidly in place. The mechanism may then be lowered to the full extent, bringing gear 150 into operative relationship to its lap. During the final part of the downward movement of the link 154, the cross-head 160 seats on the ring 161, preventing further downward movement of the shaft 159, and a thrust is transmitted through the springs 158 to the cylindrical member 149, whereby the downward thrust imposed on the latter by the springs 166 is increased, thus increasing the wedging action on the internal teeth of gear 150.

Obviously, gear 150 may be removed by reversing the aforesaid steps. The gear may be indexed merely by elevating the mechanism sufficiently to raise the gear out of its lap, when the cross-head 160 will be out of engagement with the toothed ring 161, permitting the gear 150, shaft 159, and cylindrical member 149, to be manually rotated to index the gear.

Having thus described the invention, what is claimed as new and desired to be secured by Letters Patent is:

1. In gear lapping apparatus, gear engaging mechanism comprising a relatively fixed member, a carrier associated with said member for telescoping movement with respect thereto, gear clamping means associated with said carrier, means for causing relative movement between said carrier and said member, to withdraw the clamped gear from operative position in engagement with the lap, and automatic means for actuating said clamping means to release the gear upon initiation of such relative movement. 40.

2. In gear lapping apparatus, gear engaging mechanism comprising a relatively fixed member, a carrier movably associated therewith, gear clamping means associated with said carrier, means for moving said carrier into and out of gear lapping position, and means positively locking said gear against rotation relative to said member when in gear lapping position only. 45

3. In gear lapping apparatus, gear engaging mechanism comprising a relatively fixed member, a carrier movably associated therewith, gear clamping means associated with said carrier, and means for clamping said gear and moving said carrier and gear into gear lapping position, said clamping means being actuated as a result of 55 and during the final portion of such movement of said carrier.

4. In apparatus of the character described, a carrier member and a removable gear supporting member seated therein, the engaging surfaces of 60 said members being spherical in form, both of said members being slotted to receive a gear shaft.

5. In apparatus of the character described, a carrier member and a removable gear supporting member seated therein, the engaging surfaces of 65 said members being spherical in form, means positively locking said members against relative rotary movement therebetween about the axis of the gear to be supported, a lap support, a lap supported thereon, and means for effecting relative 70 reciprocation of said carrier member and said lap in the direction of said axis.

6. In gear lapping apparatus, gear engaging mechanism comprising a relatively fixed member, a carrier associated with said member for tele- 75

scoping movement with respect thereto, a slidable member associated with said carrier, means movable with said slidable member for clamping a gear against said carrier, means for moving said 5 slidable member to release said clamping means, and means whereby the continued movement of said slidable member serves to move said carrier and gear from gear lapping position.

7. In gear lapping apparatus having a reciprocable shaft, gear engaging mechanism comprising a casing adapted to be secured to said shaft, a carrier slidable within said casing, a member slid able within said carrier, means associated with said member for clamping a gear against said carrier, means for moving said member to release said clamping means, and means whereby the continued movement of said member serves to move said carrier and gear from gear lapping position.

8. In gear lapping apparatus, gear engaging mechanism comprising a supporting casing member, a carrier slidable within said casing, a cylindrical member slidable within said carrier, means for clamping a gear between said carrier and said 25 cylindrical member, and means for moving said carrier and gear into gear lapping position, a lap support, a lap supported thereon, and means for effecting relative reciprocation of said supporting casing member and said lap.

9. In gear lapping apparatus, gear engaging mechanism comprising a supporting casing member, a carrier slidable within said casing member, a shaft slidable in said carrier, a toothed element 30 associated with said carrier, a second toothed element associated with said shaft, means for clamping a gear between said toothed elements, and means for moving said carrier and gear into gear lapping position, a lap support, a lap supported thereon, and means for effecting relative reciprocation of said supporting casing member 35 and said lap.

10. In a gear lapping machine, the combination with a lap, of gear engaging mechanism, means for relatively reciprocating said mechanism and 45 lap to effect lapping of a gear, said gear engaging mechanism including a gear support, means for clamping a gear on the support, and a single operating means for first releasing said clamping means and thereafter displacing said gear out of 50 operative relation with said lap, whereby the gear may be removed and replaced or indexed with respect to the lap.

11. In gear lapping apparatus, gear engaging mechanism comprising a reciprocable support, a carrier associated therewith for rotative and linear movement with respect thereto, means for clamping a gear for movement with said carrier, means for effecting linear movement of said car-

rier and gear into gear lapping position, and means for clamping said carrier against rotation relative to said reciprocable support when in gear lapping position, a lap support, a lap supported thereon, and means for effecting relative reciprocation of said reciprocable support and carrier and said lap.

12. In gear lapping apparatus, gear engaging mechanism comprising a reciprocable support, a carrier associated therewith for rotative and linear movement with respect thereto, means for clamping a gear for movement with said carrier, means for effecting linear movement of said carrier and gear into gear lapping position, and toothed means for clamping said carrier against 10 rotation relative to said reciprocable support when in gear lapping position, a lap support, a lap supported thereon, and means for effecting relative reciprocation of said reciprocable support and carrier and said lap.

13. In gear lapping apparatus, gear engaging mechanism comprising a reciprocable support, a carrier associated therewith for rotative and linear movement with respect thereto, means for effecting linear movement of said carrier into and out of gear lapping position and means adapted to be actuated by such linear movement of said carrier for clamping a gear against said carrier, said carrier and gear being rotatable together when out of gear lapping position, a lap support, a lap supported thereon, and means for effecting relative reciprocation of said reciprocable support and carrier and said lap.

14. In gear lapping apparatus having a fixed lap and an axially reciprocable gear support, the combination with a gear carrier mounted on said support for movement with respect to said support and said fixed lap, of gear clamping means associated with said carrier, means for moving said carrier relative to said support to withdraw a clamped gear from said fixed lap, and means responsive to such movement and effective during the initial part of such movement for automatically releasing said clamping means.

15. In gear lapping apparatus having a fixed lap and an axially reciprocable gear support, the combination with a gear carrier mounted on said support for movement with respect to said support and said fixed lap, of gear clamping means associated with said carrier, means for moving said carrier relative to said support to withdraw a clamped gear from said fixed lap, means responsive to such movement for automatically operating said clamping means, and means for reciprocating said support and carrier as a unit to effect 40 lapping of the clamped gear.

JOHN M. CHRISTMAN.
